UNITED STATES PATENT OFFICE.

JAMES HANSEN, OF SAUGERTIES, NEW YORK.

IMPROVEMENT IN CARRIAGE-SHAFTS.

Specification forming part of Letters Patent No. 42,288, dated April 12, 1864.

To all whom it may concern:

Be it known that I, JAMES HANSEN, of Saugerties, Ulster county, State of New York, have invented certain new and useful Improvements in Attaching Thills and Poles to Wagons, Carriages, and Sleighs; and I do hereby declare the following to be a full description of the same.

The nature of my invention consists in fastening and connecting thills and poles to wagons, carriages, and sleighs with the interposition of the "jack" and screw-bolts and nuts commonly in use for such purposes by means of a pin or spindle secured to the ends of the shafts or pole and at right angles thereto, which is inserted into a box or socket, formed in the ends of the cross-bar of the shafts, when reversed or thrown back, and when righted again prevented from being withdrawn from the socket by a stud on the lower side of the spindle working into a groove in the socket or against the inner sides of a staple secured in the cross bar for that purpose; but to describe my invention more particularly I will refer to the accompanying drawings, forming a part of this specification, the same letters of reference wherever they occur referring to like parts.

Figure 1 is a plan view of the thills, showing their mode of attachment to the axle-tree of a wagon, and also one of the thills reversed or thrown back to exhibit the mode of attaching it to the cross-bar. Fig. 2 is a detached view of the spindle, showing the stud on its lower side for locking it into the socket. Fig. 3 is an end view of the thill, showing its connection with the cross bar. Fig. 4 is a longitudinal cut section of the end of the thill and cross bar through the line x' , Fig. 1. Fig. 5 is an end view of the cross-bar through the line $x^2 x^2$, Fig. 4. Fig. 6 is a transverse cut section of the spindle and cross bar through the line $x^3 x^3$, Fig. 4.

Letters A are the thills, having secured on their inner ends, by suitable clips, B, and bolts C, metallic spindles D, of some six to nine inches (more or less) in length by one-half to one inch in diameter, as may be deemed necessary. On the lower side of the spindle is

formed a stud, E, the object of which is to lock the spindle into a box or socket, F, inserted, or formed by channeling, into the end of the cross-bar G, connecting the ends of the thills together. In wood cross-bars the recess for the spindle is formed by channeling or cutting a section out of the lower sides of the ends of the bar, and driving a band of metal, H, on the end of it and a staple, I, up into the bar just in front of the stud E, so that when the shafts have been righted they cannot be disengaged from the cross-bar unless reversed again, when the stud can be withdrawn through a groove, J, formed in the upper part of the recess for that purpose.

It will be obvious that where a metal box or socket is used as a receptacle for the spindle they will have longitudinal and annular grooves formed in them for the insertion and operation of the stud. It will be obvious also that packings K, of leather or other suitable materials, are contemplated as essential to the working of the spindle, and therefore I do not limit myself to the use of any particular kind of packing I may desire to use. Letters L are braces for connecting the thills to the axle-tree M.

The operation of my invention is, first, the cross bar is secured to the axle-tree or other suitable part of the vehicle by proper braces of metal for that purpose. The wagon is then cramped, (though this may not always be necessary,) and one of the thills is then reversed, as shown in Fig. 1, with the stud upward. In this position the spindle is inserted into the socket until home, when the thill may be righted, and the coupling of the same with the cross bar is completed.

Having now described my invention, I will proceed to set forth what I claim and desire to secure by Letters Patent of the United States—

The combination of the spindle D, having a stud, E, thereon, with the socket F and cross-bar G, as hereinbefore described, and for the purposes set forth.

JAMES HANSEN.
